AMMUNITION

Ernest G. Whipple, Stratford, Conn., assignor to
Remington Arms Company, Inc., a corporation
of Delaware

Application September 28, 1935, Serial No. 42,579

4 Claims. (Cl. 102—26)

This invention relates to ammunition, particularly projectiles, and will be described with particular reference to projectiles for small arms, although it is to be understood that its desirable features may be utilized in ordnance projectiles as well.

More particularly, the invention contemplates a cartridge and a projectile of advanced and distinctive ballistic properties. While of light weight and susceptible to comparatively easy manufacture from very inexpensive materials, the projectile is adapted to be propelled with great accuracy at a high velocity and possesses great power of penetration.

In the use of firearms by law enforcement officers difficulties have been introduced by the use of the so-called "bullet-proof" vest. Ordinary small arms projectiles are, generally speaking, of two types; those made entirely of lead or alloys consisting chiefly of lead; and those comprising a lead core encased or partly encased in a jacket of a harder metal such as an alloy of 95% copper with 5% zinc, commonly known in this art as "gilding metal." Jacketed projectiles in general are fired with a higher velocity and have greater penetration than lead projectiles, but even jacketed projectiles cannot be fired from hand guns of the sort ordinarily used by law enforcement officers with sufficient velocity to insure penetration of bullet-proof vests.

In one aspect, the present invention contemplates a bullet or projectile capable of penetrating bullet-proof vests; however, the projectile has other uses and fills other long felt needs. For example, the demand for increased speeds and flat trajectories has led to reduction in bullet weights. The caliber (diameter) of a given bullet cannot be altered, hence with a given material weight can only be reduced by shortening and/or forming large cavities in heel and/or point. Carried beyond certain very narrow limits, these practices seriously impair accuracy. Additional complications develop when it is necessary to maintain a standard cartridge length.

The improved projectile is illustrated in the accompanying drawing, in which:

Fig. 1 shows a typical cartridge comprising a projectile or bullet embodying the present invention.

Fig. 2 shows the bullet alone.

Fig. 3 is a section of one type of mushrooming bullet embodying the invention.

Fig. 4 is a section of an alternative form of mushrooming bullet.

Fig. 5 shows a mushrooming bullet of the type shown in Fig. 3, after impact with a target.

It has been found that commercial or substantially pure zinc may be readily formed into bullets which may be projected from hand guns and low-power rifles with a much higher velocity than any previously known bullets, and that such bullets have an extraordinary penetrating power. The raw material is preferably zinc in the form of rolled rods, which rods can be secured on the market. Slugs of suitable size are made by cutting from such rods and these slugs are swaged into bullets in an ordinary bullet swaging press. It has been found that, notwithstanding the hardness of zinc, the swaging requires no more power and no heavier machinery than the usual operation of swaging jacketed bullets to shape while assembling their cores and jackets. The reason for this may be found in the low friction coefficient of zinc with respect to steel. When such projectiles are assembled with the usual metallic cartridge components, the usual priming and the usual powder charge, and the resulting cartridge fired in an ordinary hand gun or rifle, the bullet is projected with a very high velocity and has an extremely high penetrating power. There seems to be no tendency whatever for fragments of the bullet to break or tear off in the barrel; and neither is there any appreciable wear on the barrel rifling. Such zinc bullets can be made from commercial zinc rod without annealing, whereas other materials, such as copper, require very thorough annealing and even when completely annealed require extremely high pressures for swaging. Further, the resulting copper bullets, when loaded into otherwise identical cartridges and fired from the same guns, develop higher pressures, have a much lower velocity, and rapidly wear out the barrel. The comparative pressures and velocities of ordinary metal point, zinc, and copper bullets, are as follows:

Cartridge	Bullet	Average velocity	Average pressure
38 S. & W. Spl.	Metal point	1077	15940
38 S. & W. Spl.	Copper	966.9	15530
38 S. & W. Spl.	Zinc	1251.8	15260
38 Super ACP	Metal cased	1252.7	27200
38 Super ACP	Zinc	1709.2	26400

Zinc bullets have about 50% greater penetrating power than the corresponding metal cased or metal pointed bullets. A standard penetration test consists in firing the bullets at a target consist-

ing of $\frac{1}{8}$ " steel plates alternating with $\frac{3}{8}$ " pine boards, the first steel plate being in front of the first board. An ordinary .38 caliber pistol bullet penetrates the first steel plate and the first board 5 and makes a dent in the second steel plate. A zinc bullet penetrates two steel plates and two boards and dents the third steel plate. In another test of revolver bullets the usual metal pointed bullet passed through one steel plate and 10 one board and broke an opening in the second plate but did not pass through. A zinc bullet penetrated two plates and two boards and broke an opening through the third plate.

The application of the invention to hunting 15 cartridges produces the long desired result of a bullet which both mushrooms and penetrates. For this purpose it is desirable to form a recess in the nose of the zinc body, which recess is filled or partly filled with a softer metal such as lead 20 or a lead alloy. One form of such bullet is illustrated in section in Fig. 3, 10 being the zinc body and 11 the soft metal core, which core projects from its recess to form a soft nose the surface of 25 which is a continuation of the surface of the zinc body. Alternatively, the bullet may be made of the "hollow point" type, the core metal not entirely filling the recess but leaving an unfilled portion adjacent the tip, as illustrated in Fig. 4. Such bullets have been found to possess very 30 satisfactory mushrooming properties, thus furnishing an extraordinary combination of high

penetration and excellent mushrooming. A bullet of the type shown in Fig. 3, mushroomed by impact with a target, is illustrated in Fig. 5. The bullet is shown as it actually lies in the pine board target, the core portion 13 being separated slightly from the zinc body 14.

It will be obvious that the bullet may have any desired exterior configuration and that if a lead core is provided this core may have a variety of shapes and sizes other than those illustrated. 10 The invention is of broad scope, and the appended claims are to be broadly construed.

What is claimed is:

1. A projectile comprising an unjacketed zinc body containing a relatively small core of a soft 15 metal.

2. A projectile comprising an unjacketed zinc body having a longitudinal recess therein, and a plug of soft metal in said recess and projecting therefrom to form the nose of the projectile. 20

3. A symmetrical and accurately shaped projectile for rifled firearms consisting substantially entirely of zinc and having a zinc surface for engagement with the bore of a firearm in which the projectile is fired. 25

4. A projectile for rifled firearms accurately and symmetrically shaped from a section of rolled zinc rod and having a zinc surface for engagement with the bore of a firearm in which the projectile is fired. 30
